KNITTING MACHINE

George Ball, Nuthall, England, assignor to Aristoc Limited, Nottinghamshire, England

Application October 11, 1937, Serial No. 168,462
In Great Britain October 12, 1936

9 Claims. (Cl. 66—110)

This invention is for improvements in or relating to knitting machines, and is particularly but not exclusively concerned with straight bar knitting machines. As is well known, in straight bar knitting machines the jack sinkers, by which the thread is progressively sunk into loops between the needles, are pushed forward in succession by a slur-cock operating on the jacks, a verge being provided on the sinker plate or falling bar for limiting the forward movement of the sinkers. Practical considerations demand that there should be some slight working clearance or play between the slur-cock, jacks, sinkers and verge. This play is usually slightly greater than the thickness of a jack sinker; thus in the case of sinkers .006" thick the play will be about .008". If the slur-cock is traversed without thread being fed, the sinkers are thrown forward against the verge to their utmost extent. When the sinkers engage a thread, however, the tension of that thread tends to prevent their being thrown forward quite so far, the variation in sinker movement being within the limits permitted by the aforesaid play. The amount to which the sinkers are thrown forward depends upon the tension of the thread; the harsher the tension the greater is the tendency for the sinkers not to travel right up to the verge. Such variation in travel of the sinkers in turn leads to a variation in the size of the loops and so it occurs that tension variations induce variations in loop size. Such tension variations are apt to occur in plating and splicing; they also occur when hose blanks are being produced on the three-carrier method, in which each of three courses is produced from a different thread, for when three different threads drawn from three different bobbins are employed it is impossible to ensure that the tension conditions are absolutely identical. This variation in stitch length leads to what is known as a "wash board" effect, and it is an object of the present invention to provide means whereby the ill effects of tension variation may be obviated or minimized.

As hereinafter appears, the aforementioned defects are cured according to this invention by the provision in a straight bar machine of a slur-cock having a resiliently loaded member which operates upon the loop-forming elements (sinkers) only at the forward extremity of their travel to press each said element against the abutment (verge). As will be understood, because each element is pressed resiliently against the abutment there is no play or clearance between the working parts which may be wholly or in part taken

up by the thread according to the tension thereof. This therefore makes for uniformity in loop size.

The invention is chiefly applicable to loop-forming or measuring sinkers and when applied to a straight bar knitting machine (in which the aforesaid abutment is identified with the verge) it is preferred to mount the slur-cock, or at least a jack-engaging part of it, resiliently.

One such construction will now be described in detail, by way of example, with reference to the accompanying drawing, in which

Figure 1 is a vertical section showing the relevant parts in a Cotton's patent or straight-bar knitting machine according to this invention, and Figure 2 is a plan, partly in section, of said parts.

According to this invention the slur-cock 10, which as usual has right and left hand inclined faces 10a, 10b, for operating upon the jacks 11 according to whether the slur-cock is traversed towards the right or towards the left, is provided with at least one spring-loaded member, which serves to complete the movement of the jacks and to press the sinkers against the verge. The spring-loaded member or members may take any convenient form, such for example as a small plate or plates, but it has been found advantageous to employ hard steel balls. Therefore at the forward extremity of each of the said jack-engaging faces 10a, 10b, there is a socket 12 in the slur-cock that houses a steel ball 13 and a spring 15. This spring presses the ball outwards until normally the periphery of the latter projects slightly beyond the operative face 35 of the slur-cock, the end of the socket being sufficiently restricted in diameter to prevent the ball from being forced out. Hence, as the slur-cock is traversed in the appropriate direction, the jacks 11 towards the termination of their forward movement are engaged by this ball which therefore causes the sinkers 16 to be pressed resiliently against the verge 17, the ball yielding sufficiently to obviate undue wear on the jacks. As will be understood, when the slur-cock is traversed in the reverse direction the other face 40 of the jack, and the ball associated therewith comes into operation.

The advantage of this arrangement is that, irrespective of the tension or stiffness of the thread, each jack sinker 16 is pressed right up to the verge 17, so that all the jack sinkers project between the needles to the same extent and sink loops of the same size. The extent to which the balls project is considerably exaggerated in 55

the drawing. In actual practice they will be allowed to project only a few thousandths of an inch:—preferably slightly more than the thickness of a jack sinker. Thus in the case of a machine equipped with jack sinkers .006" thick, the balls would be arranged to project .008" or .009".

The sockets or holes 12 may converge from their open ends, instead of being parallel as shown.

10 I claim:

1. A straight bar knitting machine such as a Cotton's Patent machine embodying a row or series of loop-forming sinkers, a slur-cock adapted to be traversed relatively to said sinkers so as to impart thereto a loop-forming movement, and an abutment functioning to limit said movement, and said slur cock having a spring-pressed member at the front corner or termination of an inclined or bevelled portion functioning to impart resilient pressure to the sinkers at the end of their loop-forming movement.

2. A knitting machine according to claim 1, wherein the slur-cock has a spring-pressed member at each front corner thereof.

25 3. A knitting machine according to claim 1, wherein the slur-cock has two oppositely inclined or bevelled portions and a spring-pressed member constitutes the front termination of each of said inclines.

30 4. A knitting machine according to claim 1, wherein the spring-pressed member is constituted by a ball.

35 5. A straight bar knitting machine embodying a series or row of loop-forming sinkers, means for slidably accommodating and guiding said sinkers, a fixed abutment or verge functioning to determine the limit of the forward movement of said sinkers, a slur cock, means for traversing said slur cock relatively to and at the rear of said sinkers, a series of displaceable jacks co-acting with said sinkers at the rear thereof, and said

slur cock having at least one spring pressed member adapted to co-act with said jacks in succession and through the intermediary of said jacks exert resilient pressure on the sinkers at the completion of their forward movement.

5 6. A knitting machine according to claim 5, wherein the slur-cock has two spring-pressed balls spaced apart at its front face, one functioning during the travel of the slur-cock in one direction and the other during the travel in the 10 opposite direction.

7. A slur cock for use on a straight bar knitting machine, having right and left hand inclined or bevelled faces for imparting a loop-forming motion to sinkers, balls housed in said 15 slur cock one at the front corner or termination of each incline and a spring co-operating with each ball and normally projecting same a limited distance beyond the front face of the slur cock.

8. In a knitting machine having movable loop-forming or measuring elements the extent of travel of which elements determines the loop size, and an abutment for limiting the loop-forming or measuring travel of said elements, the combination of a cam for advancing said elements towards said abutment; and a resiliently loaded member associated with the forward extremity of said cam for resiliently urging said elements up to the abutment at the extremity of their travel.

9. A slur-cock, for a Cotton's Patent or other 30 straight bar knitting machine in which sinkers are moved towards a verge by a slur-cock which travels along the line of said sinkers, said slur-cock being provided with an incline for advancing the sinkers, and having a resiliently mounted 35 member associated with the forward extremity of said incline for operating on the sinkers at their forward extremity of travel to urge them resiliently against the verge.

GEORGE BALL.
